TYPEWRITER PLATEN

John H. Sperry, Jamaica Plain, Mass.

Application November 1, 1933, Serial No. 696,188

3 Claims. (Cl. 197—144)

This invention relates to a rotary platen such as is employed in typewriters to support the paper and receive the impact or blow of the type in the printing operation.

5 The object of the invention is to provide a construction which will enable an impression to be produced of the same character that would be produced by a substantially lesser impact or blow of the type if the machine were operating 10 with the usual platen and without the present invention embodied therein.

While the invention is useful for various purposes, it is particularly designed to enable an ordinary typewriter to produce impressions of 15 the same character as that produced in duplicating machines such as multigraph work, thus enabling the typewriter to fill in addresses and other matter in such work in such a manner that the filled-in portions shall be of the same 20 character as the body of the work and practically indistinguishable therefrom.

The nature and objects of the invention will appear more fully from the accompanying description and drawing and will be particularly 25 pointed out in the claims.

As the invention relates entirely to the rotary typewriter platen, it is only necessary to illustrate and describe a preferred construction thereof.

30 In the drawing:

Fig. 1 is a view partially in longitudinal cross section of a rotary typewriter platen embodying the invention.

Fig. 2 is a view in transverse section taken on 35 the line 2—2 of Fig. 1.

The platen of this invention comprises essentially a rigid core, a hollow cylindrical rubber sheath, and a thin, resilient cylindrical shell. The rigid core may be made of any suitable material and is shown as chiefly formed of wood. It presents at the ends the cylindrical heads 1 and 2. These heads may be reinforced with metal portions carrying suitable gudgeons or connections by which the platen is rotarily 40 mounted and operated in the typewriting machine. For this purpose the head 1 includes the metal disk 3 having the gudgeon 4, while the head 2 includes the metal disk 5 having the elements 6 of suitable form for mounting and effecting the rotation of the platen. Between the heads 1 and 2 the intermediate section 7 of the core is of a length not less than the width of the printing area or the area over which the type operate in producing the printing impressions. The diameter of this intermediate sec-

tion is substantially less than the diameter of the heads. For a typewriter platen of ordinary size the diameter of this intermediate section should be about one-eighth of an inch less than the diameter of the heads but it may be of any lesser amount so long as the intermediate section is left of the required strength and rigidity.

The hollow cylindrical sheath is formed of rubber 8 preferably with a backing or lining of 65 fabric 9 and is preferably of the usual construction employed in typewriter platens to support the paper and receive the impact or blow of the type.

Between the sheath 8 and the rigid core is 70 mounted a thin, resilient cylindrical shell. This may be of any material suitable for the purpose. It extends at least throughout the interior of the sheath over the intermediate section of the core and fits snugly and closely against the 75 interior of the sheath. Preferably this thin resilient sheet extends the full length of the sheath and fits closely over the core heads. A thin sheet of celluloid of about .010 to .015 inches in thickness has been found particularly advantageous in securing the desired results. This thin resilient cylindrical shell is shown at 10 and closely fits the interior of the sheath throughout, while at its ends it fits closely over the core heads 1 and 2. It will be noted that the 80 sheet of celluloid is not brought into overlapping relation at its edges but presents a circumferentially and longitudinally continuous exterior cylindrical surface at the interior of the sheath throughout the printing area at least, and, as illustrated, preferably throughout the full length of the sheath. The term "continuous" is employed herein, and in the claims, not to differentiate between a shell formed from a sheet brought into cylindrical form with its edges 85 abutting and a shell formed as an integral tube of uniform thickness, nor to differentiate between a shell having a solid wall and a shell whose wall is skeletonized, but to define the uniformity or regularity of the supporting action 90 of the shell throughout the printing area both circumferentially and longitudinally for the purpose of the invention.

The shell acts normally to support the rubber sheath and maintain its cylindrical form between the core heads, but at the same time it allows the sheath to yield under the impact or blow of the type sufficiently to produce an impression of the same character that would be produced by a substantially lesser impact or 110

blow of the type upon a sheath similar to that described fitted over a solid core in the manner usual in typewriters.

The invention, as pointed out, is particularly useful in connection with any type of duplicating machine work of which the multigraph work is a leading example. The normal force exerted by the type in a multigraph machine in producing the impression on the paper is very much less than the force exerted by the type of a typewriter in producing the impression upon the paper. For example, the force exerted by the type of a multigraph is about three ounces, while that exerted by the type of the typewriter is about seven ounces. But with the present invention the same quality and character of ribbon which is employed in the multigraph work can be used in a typewriter equipped with this invention and the platen of this invention will yield under the blow of the type of the typewriter so as to produce an impression of the same character that has been produced in the multigraph work, thus enabling addresses and other data to be filled in by the typewriter and be indistinguishable from the body of the work produced by the multigraph.

Having thus described the invention, what is claimed as new, and desired to be secured by Letters Patent, is:

30 1. A rotary typewriter platen comprising a rigid core having cylindrical heads at each end with the intermediate section of a length not less than the width of the printing area and of a diameter substantially less than that of the heads, a hollow cylindrical rubber sheath surrounding the core to receive the impact or blow of the type and a thin resilient shell of

uniform thickness presenting a cylindrical surface circumferentially and longitudinally continuous throughout the width of the printing area and closely fitting the interior of the sheath and acting normally to support the rubber sheath and maintain its cylindrical form between the core heads while allowing it to yield under the impact or blow of the type sufficiently to produce an impression of the character produced by a substantially lesser impact or blow of the type upon a similar sheath fitted over a solid core.

80 2. A rotary typewriter platen comprising a rigid core having cylindrical heads at each end with the intermediate section of a length not less than the width of the printing area and of a diameter substantially less than that of the heads, a hollow cylindrical rubber sheath surrounding the core to receive the impact or blow of the type and a thin resilient shell of uniform thickness presenting a cylindrical surface circumferentially and longitudinally continuous throughout the width of the printing area and closely fitting the interior of the sheath and at its ends closely fitting over the core heads and acting normally to support the rubber sheath and maintain its cylindrical form between the core heads while allowing it to yield under the impact or blow of the type sufficiently to produce an impression of the character produced by a substantially lesser impact or blow of the type upon a similar sheath fitted over a solid core.

85 3. A rotary typewriter platen comprising the construction and acting as defined in claim 2, in which the thin resilient cylindrical shell is a 90 sheet of celluloid.
